UNITED STATES PATENT OFFICE.

GUY MILLER, OF SPRINGVILLE, LOUISIANA.

GAME.

1,402,637.

Specification of Letters Patent.

Patented Jan. 3, 1922.

Application filed July 22, 1920. Serial No. 398,067.

To all whom it may concern:

Be it known that I, GUY MILLER, a citizen of the United States, and a resident of Springville, in the parish of Livingston and State of Louisiana, have invented certain new and useful Improvements in Games, of which the following is a specification.

My present invention relates generally to games and more particularly to games involving the use of a board, movable pieces, and missile throwing devices the purpose of which is to upset the movable pieces, the board being divided into playing surfaces upon which the pieces are movable in sets toward one another; each playing surface being the objective field of the missile throwing device of the opposing player, and the two playing surfaces being separated as to form a dormant area the purpose of which is to penalize misplaced shots.

In the accompanying drawing which illustrates my invention and forms a part of this specification,

Figure 1 is a top plan view of the game board,

Figure 2 is a detail perspective view of one of the missile throwing devices,

Figure 3 is a detail perspective view of the flag carrying pieces,

Figure 4 is a detail perspective view of one of the movable game pieces, and

Figure 5 is a detail perspective view of one of the missiles.

Referring now to these figures 10 indicates the playing board which is divided into two fields, each adjacent to one end of the board, each field having a checkered playing surface 11, the two fields being separated by a central transverse space 12 which is marked "no man's land" and constitutes a dormant area in the playing of the game as hereinafter described.

Each player has a set of twelve pieces, one general and one flag piece, the set of twelve pieces and the general being of the form shown at 13 in Figure 4, preferably consisting of an upright on a base 14 which normally holds the piece in upright position in such manner that it may be readily knocked over by a missile 15 from one of the missile throwing devices, one of which is indicated at 16 in Figure 2.

Each of the flag pieces one of which is shown at 17 in Figure 3 consists of an upright pole having a flag 18 at its top and mounted on a base 19 and is disposed at the

front of the respective playing surface 11 within the respective playing field and is a non-movable piece although capable of being knocked over by the missiles 15 similar to the movable pieces 13.

Each of the missile throwing devices preferably consists of a barrel 20 pivoted to swing vertically in an upright U-shaped bracket 21 of a supporting base 22 and is movable by each player to any selected position around his playing field at his own side of the central space 12. Each barrel 20 has a movable plunger extending in one end carried by a plunger block 23 having a resilient connection 24 with the barrel.

In the playing of the game each set of pieces is placed in the respectively colored spaces along the two rear rows of the respective checkered surface 11, from which rows the pieces are movable forwardly, the players in turn having one shot at the opponent's pieces and one move on their own playing surface.

The game board preferably has a surrounding upright flange 25 beyond which the missiles 15 must not be shot, the penalty being that they shall lie dormant during the remainder of the game if they are either shot off of the board or fall in the spaces 12 between the playing fields. The thirteenth piece of each set, called the general, is movable in all directions and the object of each player is to get his own pieces in the front line of his respective checkered playing surface and prevent his opponent from doing likewise, pieces in the front lines being protected to the extent that they are not permitted to be knocked over and if one is knocked over the player knocking them over must give up one of his pieces, and one of his front line pieces if there are any in the front line as a captured man.

As the game progresses each player is entitled to shoot in turn from his supply of movable pieces of which each player preferably starts with six, and may also shoot all pieces he finds in his own playing field, being careful as above stated not to knock over any of the front line pieces of his opponent under the penalty of a captured man, and being also careful not to knock over his opponent's flag piece 17 at the penalty of a single retrograde movement of each of his several playing pieces including those which may be in his own front line. In moving their playing pieces, each player protects

his "general," which is movable in any direction on the playing surface, as far as possible, as a killed or captured general counts for twelve men and the player killing 5 or capturing the most men wins the game.

The game is both attractive and interesting and the manner of playing and means by which it is played place a premium upon accurate shooting or missile throwing as 10 well as a penalty upon inaccuracy and in this latter function the division of the playing fields or rather their separation by a dormant area, the missiles falling within which are dead during the remainder of the 15 game, cooperates to a marked extent in addition to its complete isolation of the playing fields and the prevention of intermixing of the playing pieces.

I claim:

20 1. A game consisting of a game board having two playing fields located adjacent to its opposite ends and a central space between said fields constituting a dormant area, each of said playing fields having a 25 checkered surface provided with a flag space in advance thereof, a set of movable and

over-turnable pieces on each checkered surface, an over-turnable flag piece for disposition on the flag space in advance of each checkered surface, each of said several pieces being normally upright, and a missile throwing device for each field and bodily shiftable freely thereover having for the objective of its missiles the knocking over of the movable pieces of the opposing field. 30 35

2. A game consisting of a game board having two playing fields and a dormant area separating the fields, each field having a playing surface, a series of playing pieces normally set in upright position on each 40 playing field, including a set of movable pieces on the playing surface and a non-movable piece in advance of the playing surface, and a missile throwing device for each playing field, each missile throwing device 45 being bodily shiftable over its respective playing field movable thereover to selected position and having means to discharge missiles capable of upsetting the movable and non-movable pieces of the opposing field. 50

GUY MILLER.
